UNITED STATES PATENT OFFICE.

HARCOURT C. DRAKE, OF HEMPSTEAD, NEW YORK, ASSIGNOR TO THE SPERRY GYROSCOPE COMPANY, OF BROOKLYN, NEW YORK, A CORPORATION OF NEW YORK.

ADAPTER.

Application filed December 19, 1924. Serial No. 757,123.

This invention relates to adapters especially designed for use in the radio art. More particularly this invention relates to adapters designed to permit the use of a plurality of different types of appliances within the standard sockets now provided in radio receiving instruments. These adapters are particularly designed to receive audion bulbs of various types and designs. Thus, for example, this invention has for one of its objects the provision of an adapter which will permit audion bulbs having various sized bases to be employed in connection with the ordinary sized sockets now utilized in radio receiving sets. Further, this invention has for its object the provision of adapters permitting the use of various types of audion bulbs other than the ordinary type bulbs now in use and which employ a battery to supply D. C. current for heating the filament. Thus, for example, my invention provides an adapter which will permit the use in the present type of socket of a type of audion bulb adapted to utilize the household circuit for heating the filament.

Further, this invention contemplates the provision of adapters for use with screw-base type audion bulbs as well as adapters for use with bayonet type bulbs.

The advantages of an adapter of this type will be readily apparent since sockets for receiving the audion bulbs are built into receiving sets in a very substantial manner and, especially in the high priced sets, cannot be removed except at great expense and at the danger of damage to the set.

While I have attempted to indicate some of the uses of my invention in the preceding paragraphs, it will become apparent in the following description that other uses and advantages thereof will readily be found.

In the accompanying drawings.

Fig. 1 is a vertical section through one form of adapter embodying my invention and showing said adapter applied to the ordinary type socket and supporting a screw-base type audion bulb.

Fig. 2 is a view similar to Fig. 1 but showing another form of my adapter designed to support a bayonet type audion bulb.

Fig. 3 is a plan view looking down on the adapter which I employ in Fig. 2, the bulb having been removed.

Fig. 4 is a view looking up at the bottom 55 of the adapter which I employ in Fig. 2.

Fig. 5 is a view similar to Fig. 4 and illustrating a modification of the Fig. 4 design.

Fig. 6 is a vertical section taken on another line through the adapter of Fig. 2 and showing the method of leading current to the heating element through said adapter.

Fig. 7 is another form of adapter which may embody the features of either the Fig. 1 or Fig. 2 device and showing the method of accommodating audion bulbs having bases of various sizes within a socket of standard size.

My invention can best be described by referring first to the present type of audion bulb which may be the standard De Forest bulb and the present type of socket for receiving said bulb.

The present audion bulb has four prongs and fits into a socket having four leaf springs with which the four prongs contact. Two prongs connect with the two ends of the cathode or filament and are in turn connected through two of the leaf springs to the terminals of a D. C. source of current, such as a battery. A third prong connects with the plate and through another leaf spring in the socket engages a source of D. C. current, known as the "B" battery. The fourth prong connects with the grid and the leaf spring of the socket which it engages is connected in circuit with a transformer or tuning unit or is otherwise connected in a receiving circuit.

When, however, an audion bulb of different type is employed, especially those new types of bulbs which employ a filament or heating element separate from the cathode and utilize a source of current other than a battery for heating the filament, it is quite apparent that the present socket cannot be employed because the leaf springs or contacts thereof which engage the filament or heating element cannot be connected to a source of current other than a battery, otherwise a hum will be set up in the circuit due to commutator ripple or A. C. period.

One form of such audion bulb is shown at 10 in Fig. 1 and comprises a plate 11, a grid 12, a cathode 13, which corresponds to the filament in the old type, and a separate heating element or filament 14 for heating said cathode. Said heating element 14 is supplied from a source of current of relatively high voltage and said source may be the ordinary household circuit either A. C. or D. C.

105 110

Since the heating filament in this case is not in the receiving circuit the latter will not be affected by commutator ripple or A. C. period due to the source of current supply.

5 In the type of bulb 10 shown in Fig. 1 the plate, grid and cathode are connected by wires 11', 12', 13', which extend outside of the bulb and may be led to the various points of connection.

10 It is apparent that if this type of bulb 10 is employed, three spring contacts 15, 16, 17 of the ordinary socket 20, such as is employed in standard receiving sets, may be connected to the three lines 11', 12', 13' but that separate connections are necessary for the heating element or filament 14. One form of my adapter makes provision for all of these features. This adapter is shown at A and fits directly into the socket 20 and is located therein by means of a bayonet lock which includes the pin 21 and the slot 22, one on the adapter and the other in the socket. Said adapter has embedded therein three conductor lines 11'', 12'' and 13'' which terminate on the outside of the adapter in terminals 11₁, 12₁, 13₁. Also embedded in-said adapter A are two conducting lines 23, 24 terminating in terminals 23', 24' on the outside thereof, said lines 23, 24 terminating one in a post 25 in the bottom of the adapter and the other in a contact on the inner wall thereof. The bulb 10 may be provided with a base which may be in the form of a screw socket or plain and the heating element 14 may have one terminal thereof projected through the base and terminating in a contact 26 and the other terminal extending to the side of the base and connecting at 27 to the conducting side walls of the base. It is apparent that when the bulb 10 is inserted within the adapter, either longitudinally, if the base is a plain cylinder, or by screw threading, if it is of the type shown in Fig. 1, that the contact 26 will engage contact 25 and contact 27 will be in engagement with conductor 24 so that by connecting terminals 23', 24' to a suitable source of current, which may be the household circuit, the heating element 14 will be energized. At the same time the plate, grid, and filament connections 11', 12' and 13' connecting with the terminals 11₁, 12₁ and 13₁ will be connected in the receiving circuit by contacting with leaf springs 15, 16, 17. If desired a fourth, but dead or inactive, prong 18 may be provided to engage the fourth contact spring of the socket in order to support the adapter A at all points and balance the same.

Another form of my adapter is illustrated 60 in Fig. 2 and is designated A'. This adapter is designed especially for use with the bayonet type A. C. audion bulb which is inserted into the socket, or in this case into the adapter merely by a linear movement. The 65 adapter A' is inserted in the socket 20 in a

manner similar to the adapter A. In this case, however, the bulb 10 is provided with five conducting lines corresponding to 11', 12', 13', 14', 14'', which extend straight downwardly into the base and not through the glass wall thereof. Upon the bottom of the base is provided five prongs connected to the said five lines, respectively. As in the previous case three of these prongs, one each for the plate, grid and filament, must in some manner make contact with the leaf spring contacts 15, 16, 17, while the other two prongs must make contact with terminals leading to a suitable source of current. For this purpose the adapter A' is provided with three conducting receptacles 31, 32, 33 adapted to receive the three prongs marked P, G and C, for the plate, grid and cathode, respectively, said receptacles 31, 32, 33 having extensions extending through the base of the adapter A' and engaging the leaf spring contacts 15, 16 and 17 respectively of the socket 20.

As shown in Fig. 6 the remaining two prongs H', H'' connected to the conductors 14', 14'' of the heating filament also enter receptacles 34, 35 fixed in the base of the adapter A', but these receptacles 34, 35 do not extend through the base of the adapter as in the case of the other receptacles but connect with conductors 36, 37 leading to the terminals 38, 39 on the outside of the adapter so that said heating element can be connected to a suitable source of current, preferably a high voltage source such as the household circuit.

In this case also four prongs extend downwardly from the bottom of the adapter as shown in Fig. 4 for engaging the four prongs of the socket. In this case also one prong may be a dead prong merely for the purpose of providing an additional point of support for the adapter or it may be connected to the prong which forms the extension of a receptacle 33 which extends through the base of the adapter and engages the cathode prong C. This arrangement is desirable because in some circuits the leaf spring 17, which is ordinarily connected to one terminal of the cathode, may be the one in circuit or it may be the fourth leaf spring, not shown, and which is ordinarily connected to the other terminal of the cathode that is in circuit. In the latter case, if the dead prong C' were not connected to the live prong C, the filament would not be in the circuit. By bridging the two prongs C, C', either type of circuit may be employed, that is, a circuit which includes the fourth leaf spring, not shown, and with which the fourth or dead prong engages, or the circuit which includes the leaf spring 17 with which the live prong of the filament engages.

It is apparent from the above description that I have provided an adapter which permits bulbs of the type which require a dif-

ferent source of current than those normally used in the ordinary receiving circuits to be employed in connection with the ordinary type socket at present in said sets. The adapter is also serviceable in permitting the use of bulbs having bases of various sizes either smaller or larger than the standard sockets 20 permit. Thus the ordinary D. C. type bulb may be provided with a base that is smaller 10 or larger than the said socket or the types of bulbs described in Figs. 1 and 2 may be provided with bases of smaller or larger sizes than the said socket. My adapter can very easily be so formed as to take care of this 15 contingency either alone or in connection with the feature already described of permitting some different source of current.

Fig. 7 illustrates one manner of taking care of various sized bases. This consists 20 merely in shaping the adapter with a lower portion which fits into the socket and provided with an opening or receptacle of the size adapted to cooperate with the particular base of the audion bulb used.

In accordance with the provisions of the 25 patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of 30 these may be altered and others omitted without interfering with the more general results outlined, and the invention extends 35 to such use.

Having described my invention, what I 40

claim and desire to secure by Letters Patent is:

1. An adapter for audion tubes having a plate, a grid, a cathode, and a heater element for said cathode, said adapter having means 45 in its base for effecting connections to said plate, grid and cathode and having means in its side wall for effecting connections to said heater element.

2. An adapter for audion tubes having a 50 plate, a grid, a cathode, a heater element for said cathode, and five leads connected to the foregoing tube parts and projecting from said tube, said adapter having a plurality of receptacles in its base for receiving the 55 terminals of said leads, the receptacles connected to said plate, grid and cathode extending through the base of said adapter, said adapter having connections in the side walls thereof connected to the remaining receptacles containing the heater element leads. 60

3. An adapter for audion tubes having a plate, a grid, a cathode, a heater element for said cathode, and five leads connected to the foregoing tube parts and projecting from 65 said tube, said adapter having a plurality of receptacles in its base for receiving the terminals of said leads, the receptacles connected to said plate, grid and cathode extending through the base of said adapter to form 70 prongs on the lower surface thereof, and an additional prong on the lower surface of said base, said adapter having connections in the side walls thereof connected to the remaining receptacles containing the heater element 75 leads.

In testimony whereof I have affixed my signature.

HARCOURT C. DRAKE.
